UNITED STATES PATENT OFFICE.

ANNA OLSSON, OF SOUTH MANCHESTER, CONNECTICUT, ASSIGNOR TO CHENEY BROTHERS, OF SOUTH MANCHESTER, CONNECTICUT, A CORPORATION OF CONNECTICUT.

DESIGN FOR TEXTILE FABRIC.

41,890.

Specification for Design.

Patented Oct. 31, 1911.

Application filed June 23, 1911. Serial No. 634,960 $\frac{1}{2}$. Term of patent 3 $\frac{1}{2}$ years.

To all whom it may concern:

Be it known that I, ANNA OLSSON, a citizen of the United States, residing at South Manchester, Hartford county, Connecticut, have invented a new, original, and ornamental Design for Textile Fabrics, of which the following is a specification, reference being had to the accompanying drawings, forming a part thereof.

The drawing illustrates a portion of a textile fabric showing my design.

I claim:

The ornamental design for a textile fabric as shown.

ANNA OLSSON.
